UNITED STATES PATENT OFFICE.

CONRAD THYSSEN, OF AACHEN, GERMANY.

METHOD AND MEANS FOR FEEDING ARTICLES.

Application filed June 18, 1924. Serial No. 720,879.

In many machines designed to work upon cylindrical articles, such as wire-shanks used in the manufacture of needles, the articles are fed to the working place in a continuous row and the ends to be worked upon of the articles must be uniformly dressed or alined in order to secure an accurate working of the machines.

Now, the present invention has for its object to devise a method and device by means of which the aforesaid aligning of the ends to be worked upon of the cylindrical articles may be effected in a simple and efficient way. This object is essentially attained by exerting on the articles fed as stated a pressure from two opposite sides for yieldably holding them, and while thus held imparting an endwise shifting motion to some or all of the articles for bringing their said ends into one common line.

For the purposes of the invention, I shall now describe it with reference to the accompanying drawing which diagrammatically illustrates, by way of example, two embodiments of the device forming part of the invention.

In the drawing:

Fig. 1 is a view, partly in section, of the first embodiment;

Fig. 2 is a side elevation of the same, as seen from the left of Fig. 1,

Fig. 3 is a section along the line 3—3 of Fig. 1,

Fig. 4 is a view, similar to Fig. 1, of a modified form,

Fig. 5 is a side elevation of the device according to Fig. 4, seen from the left,

Fig. 6 is a section along the line 6—6 of Fig. 4.

The several figures of the drawing show only those parts of the device which are necessary for the understanding of the invention, while the means for imparting the feeding motion to the cylindrical articles and the means for actuating the several parts of the device are omitted for the sake of clearness and because they may be of any approved construction.

Referring now to the drawings the embodiment shown in Figs. 1-3 which is the primitive form of my invention, will be described first. 7 is a feed track which may be arranged vertically or horizontally and which consists of two walls 8 and 9 between which the cylindrical articles, for instance wire-shanks 10, are fed in a row in the

direction of the arrow *a* to a working place. It is assumed that the shank ends lying on the left-hand side of Figs. 1 and 3 should be worked upon and therefore must be alined.

To this end the following means are used. The track wall 9 is provided with a recess 11 in which is mounted a pressure member 12 for instance in the form of a plunger. The member 12 is adapted to be moved in the direction of the arrow *b* and serves to press the group of shanks which lies between it and the opposite track wall 8, against this wall which constitutes another pressure member.

The pressure with which the shanks 10 have to be pressed between the member 12 and the wall 8 must be greater than the relative frictional resistance between the shanks 10 themselves.

In order to obtain a uniform yieldable pressure on the shanks and a high frictional resistance between them and the member 12 the end face of the latter is covered with a layer 13 of rubber or any other elastic material.

Arranged laterally of the shank ends to be worked upon is a slide 14 which is movable towards and away from said ends in the direction of the arrow *c*. While the shanks 10 are being yieldably held between the pressure member 12, 13 and the track wall 8, the slide 14 is moved against the shank ends to be worked upon and shifts the shanks endwise individually or in groups, thereby bringing the said ends into one common line, as will be seen from Fig.

1. Owing to the friction of the shanks between the pressure member 12 and the track wall 8 no shank will be shifted farther than the slide 14 is moved. As soon as the group of shanks has been dressed, the slide 14 and the pressure member 12 recedes so that the shanks are released for further feeding.

In order to attain that all of the shanks are delivered to the working place uniformly alined, the described alining operation is repeated in shorter or longer spaces of time which depends on the speed at which the shanks are conveyed through the feed track 7.

If it is desired to have the shanks continue their feed motion during the alining operation, the pressure member 12 and the slide 14 must likewise be moved in the direction of feed as long as they are operating on the shanks and thereafter be returned to their initial positions. This to and fro movement is indicated by the arrow *d*.

With the device according to Figs. 4-6

which embodies the preferred form of my invention and which is best suited for actual use, the movable slide 14 is replaced by a stationary or adjustable fence 14', while the pressure member 12 when pressing on the shanks 10 is moved in the longitudinal direction of the shanks (see arrow f), thereby shifting them so that the ends to be worked upon are caused to strike against 10 the fence 14' whereby such ends are aligned. If, with this device, the shanks should be fed through the track 7 uninterruptedly, it is only necessary to impart to the pressure member 12 a movement in the direction of 15 the feed motion of the shanks; that is to say, besides the movement for pressing the member 12 against the shanks and lifting it from the same, the member has an additional movement imparted to it in the oblique direction indicated by the arrow g.

Various possible embodiments of the invention and various changes in the embodiments described may be made, all within the scope of the subjoined claims.

25 Having thus described my invention, what I claim as new and desire to secure by Letters Patent, is:—

1. The combination with a track for feeding cylindrical articles in a row to a working place, of a device for alining the ends of the articles to be worked upon, comprising pressure members arranged on both sides of the row of cylindrical articles, one of the pressure members being formed by one of the track walls and the other pressure member consisting of a plunger adapted to be moved through a recess of the other track wall into and out of engagement with the cylindrical articles and designed to yieldably press and hold the articles against the first-said track wall, and means for imparting an endwise shifting motion to some or all of the articles held between the pressure members for bringing the ends to be worked 40 upon into one common line.

2. The combination with a track for feeding cylindrical articles in a row to a working place, of a device for alining the ends of the articles to be worked upon, comprising a fence extending laterally of the feed track at a certain distance from the same, a recess in one of the track walls and a pressure member in the said recess, this pressure member being adapted to intermittently engage a series of the cylindrical articles for yieldably pressing the same against the opposite track wall and movable both in the direction of feed of the articles and in the 50 direction of their longitudinal axes for shifting the articles endwise with their ends to be worked upon against the said fence without interrupting the feed of the articles.

3. A method of aligning particular ends of cylindrical articles where such articles are being fed in a continuous row in mutual

contact, consisting in providing a relative lateral movement between successive groups of articles and an aligning member to simultaneously align the similar ends of the articles of a group while exerting a pressure upon the articles of the group to a degree sufficient to prevent movement of the articles of that group as a result of their frictional contact with each other.

4. A method of aligning particular ends 75 of articles which are being fed in a continuous row in mutual contact, consisting in a relative movement of successive groups of the articles as a unit with relation to an aligning member to align the similar ends 80 of the articles of such group while preventing movement of any article of the group resulting from its frictional engagement with an adjacent article.

5. A method of aligning particular ends 85 of cylindrical articles which are being fed in a continuous row in mutual contact, consisting in holding the articles of a particular group against similar lateral movement incident to their frictional engagement one 90 with another, and aligning the similar ends of the articles of the group of articles so held.

6. A method of aligning particular ends 95 of articles being fed in a continuous row in mutual contact, consisting in applying pressure to a group of the articles sufficient to overcome the tendency of the articles of such group to move together under their relative frictional engagement, and aligning the 100 similar ends of the articles of the group under a pressure exceeding that of the first mentioned pressure.

7. A method of aligning similar ends of articles which are being fed in a continuous 105 row in mutual contact, consisting in holding the articles of a group against their tendency to move laterally together as a result of their frictional engagement, and thereafter moving such group relatively to an aligning 110 member to move the selected ends of the articles of the group into alignment without regard to the holding means.

8. A method of aligning the similar ends 115 of a series of cylindrical articles fed in a continuous row in mutual contact, consisting in moving the articles of a group relatively and laterally to align their similar ends while at the same time preventing the movement of any one article of the group 120 being transferred to an adjacent article through the frictional engagement of such articles.

9. A trackway for feeding cylindrical articles in a row in mutual contact, an aligning means with which selected ends of the articles may be made to contact in successive groups to align such ends, and means whereby any one of the articles of the group 125 being aligned is held against movement re-

sulting from its frictional engagement with the adjacent articles of the group.

10. A trackway for feeding cylindrical articles in a row in mutual contact, an aligning member relative to which the articles of a group may be moved to an extent to align the similar ends of the articles of such group, and a pressure means acting upon all the articles of the group to prevent any one article thereof from moving solely through its frictional cooperation with the adjacent articles of the group.

11. A trackway for feeding cylindrical articles in a row in mutual contact, a fixed aligning member against which the similar

ends of a group of articles may be moved to align said ends, pressure means cooperating with the articles of the group serving to exert a pressure upon said articles to a degree sufficient to prevent any one article of the group from moving as a result of the frictional engagement between such article and the adjacent articles of the group, and means for operating the pressure means to bodily move the group toward the aligning member for aligning the ends of the articles of such group.

In testimony whereof I have signed my name to this specification.

CONRAD THYSSEN.
